COMBINED CABINET AND ACCESSORY TRAY UNIT

Essie M. Reid, 12 Rita Lane,
North Syracuse, N.Y. 13212

Filed Nov. 7, 1969, Ser. No. 19,979

Term of patent 14 years

Int. Cl. D6—01

U.S. Cl. D33—19

FIG. 2

FIG. 1 is a perspective view of the combined cabinet and accessory tray unit, embodying my new design; and FIG. 2 is a side elevational view thereof.

The appearance of the side portions of the cabinet is the same throughout the periphery thereof.

I claim:

The ornamental design for a combined cabinet and accessory tray unit, substantially as shown and described.
